(57) **CLAIM**

The ornamental design for an inspection lighting device, as shown and described.

DESCRIPTION

FIG. 1 shows a front side elevational view of the inspection lighting device, the rear side elevational view being a mirror image thereof and the bottom view being identical to the front side elevational view.

FIG. 2 shows a left side elevational view of the inspection lighting device.

FIG. 3 shows a right side elevational view of the inspection lighting device.

FIG. 4 shows a top plan view of the inspection lighting device; and,

FIG. 5 shows an enlarged vertical longitudinal sectional view (along the center line A—A of the right side elevational view).
